UNITED STATES PATENT OFFICE.

LAMBERT SCHMIDT, OF BROOKLYN, NEW YORK, ASSIGNOR TO RADIOTIVE CORPORATION, OF BROOKLYN, NEW YORK.

TELEPHONE RECEIVER OR TRANSMITTER.

Application filed June 26, 1922. Serial No. 570,670.

To all whom it may concern:

Be it known that I, LAMBERT SCHMIDT, a citizen of the United States, and a resident of Brooklyn, county of Kings, and State of New York, have invented a certain new and useful Improvement in Telephone Receivers or Transmitters, of which the following is a description.

This invention relates to telephone receivers or transmitters of the magneto type and more particularly concerns the vibration transmitting connection between the sound producing diaphragm of the instrument and the magnet armature.

15 In Patent No. 1,452,850, granted to me on April 24, 1923, I have described and claimed a telephone transmitter or receiver having certain improved features of construction in connection with which the present invention is particularly designed to be employed.

More particularly, the present invention broadly comprehends an improved protected universal pivotal connection between the 25 diaphragm vibrating rod and the armature so that said rod will at all times remain substantially perpendicular to the plane of the diaphragm, thus insuring a loud distinct emission of the voice tones and greatly increasing the sensitiveness of the instrument to minute fluctuations in polarity of the alternating currents.

In one embodiment of the invention which 35 I have found highly satisfactory in practical use, the armature which is fulcrumed intermediate of its ends is provided at one end with an opening through which the end of the diaphragm rod is loosely engaged. At one end of said opening a groove or channel is formed in the armature in which a head on the end of said rod has free rocking movement. In order to prevent shifting movement of the rod through said opening in one direction and the accumulation 45 of grit or dirt in the groove or channel which would interfere with the free pivotal or rocking movement of the end of the rod, I preferably provide a split sleeve removably engaged upon the armature end over the slot 50 or channel therein and the headed end of the diaphragm rod. Thus, in the slight arcuate movement of the end of the armature between the opposed poles of the magnet, the rod connected to the diaphragm will always 55 remain in its normal perpendicular position

with respect to the plane of the diaphragm so that the rod will not exert a lateral torsional strain upon the diaphragm which would interfere with the amplitude of its vibratory movement.

With the above and other objects in view, the invention consists in the improved diaphragm operating connection for instruments of the character referred to and in the form, construction and relative arrangement of the several parts, as will be herein-after more fully described, illustrated in the accompanying drawings and subsequently incorporated in the subjoined claims.

In the drawing wherein I have illustrated one preferred and satisfactory embodiment of the invention and in which similar reference characters designate corresponding parts throughout the several views,

Figure 1 is a sectional view through a telephone receiver or transmitter, the cover or casing for the magnet structure and the ear piece being omitted;

Figure 2 is an enlarged detail section taken on the line 2—2 of Figure 1;

Figure 3 is a section taken on the line 3—3 of Fig. 2, and

Figure 4 is a detail end elevation.

In the accompanying drawing, for purposes of illustration, I have shown a conventional form of permanent magnet 5 suitably secured to the rear side of the front plate 6, the latter being of a suitable non-magnetic material. To opposite ends of the permanent magnet 5 the pole pieces 7 are suitably fixed, said pole pieces being provided with angularly disposed shoes 8 at their opposite ends, the corresponding shoes of the pole pieces being disposed in the same plane and in opposed relation to each other. Between the spaced pole shoes the electromagnet coil 9 is arranged, said coil being wound on a cylindrical spool of non-magnetic material. Through the bore of this spool the cylindrical armature 10 is disposed and has its opposite ends normally positioned centrally between the opposed pole shoes and out of contact with the end faces thereof. The cylindrical armature is fulcrumed at a point approximately midway between its ends in the bore of the coil spool. As the specific fulcrum or mounting for the armature constitutes no essential feature of the present invention, but is fully illustrated, described and claimed in my issued patent, such

mounting will not be herein further referred to.

The front plate 6 is formed with the usual annular marginal rib 11 to which the outer edge of the flexible diaphragm 12, preferably of mica, is suitably secured.

The inner end of the cylindrical armature 10 has a diametrically reduced extension 13. This extension is provided at one side in 10 its periphery with a transverse groove or channel 14 with which the opening 15 extending through said armature extension communicates at one of its ends. The diaphragm vibrating rod 16 is threaded at one 15 end and extended through a central opening in the diaphragm 12 to receive the nut 17, said nut after proper adjustment, being fixed in position by coating the same with shellac or by other suitable means. The rod 16 at its other end is engaged through the 20 opening 15 in the reduced end of the armature and it will be noted that this opening is of slightly greater diameter than said rod. This end of the rod terminates in a head 18 25 which is of greater diameter than the opening 15 and is loosely positioned in the groove or channel 14 so that said head may have a free rocking motion in said channel in the slight arcuate movement of the armature end between the pole shoes during 30 which movement the axis of the opening 15 will be positioned out of coinciding relation with the axis of the rod 16. Thus it will be obvious that in the vibratory movement of 35 the armature the only movement transmitted to the rod 16 is directly in the line of its axis, there being no lateral deflection of this rod which would result in torsional strain on the diaphragm 12.

40 The relative movement of the armature end and the rod 16 axially of said rod is prevented by means of a split resilient metal sleeve 19 which is removably engaged over the reduced end 13 of the armature and entirely covers and conceals the slot or channel 13. The head 18 of the rod 16 is preferably formed with a convex end face for rocking contact with the inner face of the sleeve 19. The sleeve also serves to prevent 45 the entrance of particles of grit or dirt to the groove 14 which might possibly interfere with the free universal pivotal action of the rod end in the opening 15 of the armature. In the arcuate movement of the 50 armature in one direction as it is attracted by the pole shoe 8 at one side thereof, the rod 16 is axially moved in one direction by the pressure of the sleeve 19 against the head 18, while when the armature end moves in 55 the opposite direction from its normal position under the attraction of the other armature shoe 8, the rod 16 is pulled inwardly by the coaction of the end 13 of the armature with the head 18 on said rod. In the movement 60 of the armature in either direction, it

is apparent that the end of the rod 16 may have a free universal swivelling or pivoting movement with respect to the armature so that it will at all times maintain a perpendicular position relative to the plane of the 70 diaphragm 12.

From the foregoing description, the construction and operation of the device will be readily understood. In a very simple construction, I have provided a protected 75 universally movable connection between the armature and the diaphragm which will be instantly responsive to the slightest pulsations or variations in polarity of the alternating voice currents when the instrument is used as a receiver to transmit vibrations of maximum amplitude to the diaphragm 12. It is obvious that the same highly sensitive action will take place when the instrument is used as a transmitter and the sound waves are impressed upon the vibratory diaphragm. It will further be apparent that while I have herein referred to an adaptation of the present improvement for use in 80 connection with magneto telephones, the device might also possess other capabilities and be advantageously applied for use in connection with the armature of a magnetic structure intended for more or less general 85 application in the art. In such other applications of the invention it may be found desirable to resort to certain minor structural modifications.

Accordingly, it is to be understood that while I have herein shown and described 100 one practical and satisfactory embodiment of the device, the same may nevertheless be incorporated in numerous other alternative structures and I, therefore, reserve the privilege of resorting to all such legitimate 105 changes in the form, construction and relative arrangement of the several parts as may be fairly embodied within the spirit and scope of the invention as claimed.

I claim:

1. In combination with the vibratory armature of a magnetic structure and a part actuated thereby, means for transmitting the vibrations of the armature to said part, comprising a rigid element having a fixed 115 connection at one of its ends to said part, said armature being provided with a seat, said element having a part at its other end loosely engaged on said seat, and means carried by the armature extending over said seat to retain said part in rocking contact therewith.

2. In combination with a vibratory armature of a magnetic structure and a part to be actuated thereby, a rigid element having a fixed connection at one of its ends to said part, said armature being provided with a seat, said element having a part at its other end loosely engaged on said seat, and a member having detachable frictional 130

engagement with the armature and extending over said seat to retain said part in rocking contact therewith.

3. In combination with the vibratory armature of a magnetic structure and a part to be actuated thereby, a rigid element having a fixed connection at one of its ends to said part, said element at its other end extending through an opening in the armature and terminating in a head, said armature and the connected end of said element having relative universal pivotal movement in the vibratory movement of the armature, and means detachably engaged with the armature to retain said armature and the connecting element in assembled co-operative relation.

4. In combination with the magnetic structure of a magneto telephone having a vibratory armature and a diaphragm to be actuated thereby, a rigid element having a fixed connection at one of its ends to said diaphragm, the other end of said element and the armature being provided with co-acting means affording a universally movable connection therebetween, and protective means detachably engaged with the armature and acting to prevent relative movement of the armature and said element in the axial direction of the latter during the vibratory movements of the armature.

5. In combination with the magnetic structure of a magneto telephone having a vibratory armature and a diaphragm to be actuated thereby, said armature being formed with a cylindrical extension at one end, a rigid element having a fixed connection at one of its ends to said diaphragm, the cylindrical armature extension having an opening through which the other end of

said element is loosely engaged, said armature extension being further provided with a groove in one side intersecting said opening and said element terminating in a head having a free rocking movement in said groove, whereby said element will at all times remain in a perpendicular position relative to the plane of the diaphragm, and means for preventing relative movement of the armature and said connecting element axially of the latter in the vibratory movements of the armature.

6. In combination with the magnetic structure of a magneto telephone having a vibratory armature and a diaphragm to be actuated thereby, said armature being formed with a cylindrical extension at one end, a rigid element having a fixed connection at one of its ends to said diaphragm, the cylindrical armature extension having an opening through which the other end of said element is loosely engaged, said armature extension being further provided with a groove in one side intersecting said opening and said element terminating in a head having a free rocking movement in said groove whereby said element will at all times remain in a perpendicular position relative to the plane of the diaphragm, and a detachable resilient sleeve adapted to be engaged upon the cylindrical armature end over the groove therein to prevent relative movement of the armature and said element in the axial direction of the latter during the vibratory movements of the armature.

In testimony that I claim the foregoing as my invention, I have signed my name
hereunder.

LAMBERT SCHMIDT.
